REMOTE CONTROL DEVICE FOR
AUTOMATIC PHONOGRAHS

Russell I. Wilcox, Berwyn, Ill., assignor to The
Rudolph Wurlitzer Company, North Tonawanda, N. Y., a corporation of Ohio

Application November 12, 1938, Serial No. 239,957

7 Claims. (Cl. 177—353)

This invention relates to certain new and useful improvements in remote control devices for automatic selective phonographs and the like.

It has for one of its objects to provide a remote control device of this character which is simple in construction and reliable in operation, and which is so designed and constructed as to be readily applicable for operative connection to the multi-selective type of phonograph, and whereby 10 a patron at a remote point from the instrument may readily select desired records.

Another object of the invention is to provide a remote, coin-controlled selective device which is particularly applicable to the push-button type 15 of selective phonograph, and wherein a selection made at the wall box of the device is automatically registered with the companion push button of the instrument, after which other automatic means provide for the movement of such push button 20 to a selective position.

Other features of the invention reside in the construction and arrangement of parts herein-after described and particularly pointed out in the appended claims.

25 In the accompanying drawings:

Figure 1 is a side elevation, partly in section, of the selective push button assembly of an automatic phonograph showing my invention associated therewith. Figure 2 is a central, longitudinal section thereof. Figure 3 is a cross section taken on line 3—3, Figure 1. Figure 4 is a front elevation, with the cover removed, of the selector-controlled wall box and associated parts. Figure 5 is a side view, partly in section, of the 35 wall box and associated parts. Figure 6 is an enlarged transverse vertical section taken on line 6—6, Figure 5. Figure 7 is a detail face view of the selector-registering drum and associated parts. Figure 8 is a fragmentary perspective view 40 of the remote push button assembly. Figure 9 is a wiring diagram of the remote control device.

Similar characters of reference indicate corresponding parts throughout the several views.

This remote control mechanism has been designed more particularly for the selective type of phonograph, such for example as the multi-selector type shown in my Patent No. 2,002,236, dated May 21, 1935, and wherein the selection of records at the phonograph is effected by push rods or buttons and which elements determine the playing of the records selected. In the present invention, I employ remote control means for automatically actuating the selector rods or buttons of the phonograph, such means comprising 55 a revolving selector control arm disposed in oper-

ative relation with the selector push buttons of the phonograph to be selectively positioned in line with one or another of the buttons corresponding to the record selected for play at the wall box or remote control station and to be axially shifted 5 at a predetermined time to move the selected push button to an operative position to select a record for play; and actuating mechanism operatively associated with such control arm for governing its selective operating movements and for 10 governing the restoration of such parts to their initial position. This remote control mechanism is coin-controlled so that upon the deposit of a coin and the selection of a desired record at the remote control station, the selecting operation will 15 subsequently be automatically performed at the phonograph.

In Figures 1 and 2 of the drawings, the numeral 10 indicates the selector button panel of the phonograph shown in my aforesaid patent and 11 20 indicates the record-selecting push rods or buttons which are disposed in annular fashion to correspond in number to the records borne by the instrument. These push rods are suitably guided for axial movement to and from a selective 25 position in suitable supporting plates 12, 13 and 14, and when moved to a projected selected position, their inner ends are disposed in the path of a rotatable stop arm 15 applied to the selector shaft 16 of the phonograph so that when the 30 selector mechanism of the latter is rendered operative the selector shaft 16 is rotated and as its arm 15 abuts one or another of the projected push rods, it arrests the rotation of the selector shaft to in turn effect the automatic selection of 35 the record desired for play, all as shown in my Patent No. 2,002,236. Spaced collars 17, 18 fixed 40 on each of the push rods, serve to limit the projected and retracted movements of such rod, the collar 17 abutting the front side of the supporting plate 13, when its push rod is projected, and the companion collar abutting the rear face 45 of such plate when the push rod is retracted to its initial position.

Associated with the push button assembly of 45 the phonograph, is a selector-control arm 19 which is fixed radially to a combined rotatable and axially shiftable shaft or plunger 20 supported in the adjoining plates 12, 13 and disposed axially of the center about which the push 50 rods 11 are arranged. Fixed on the hollow front end of the shaft 20 is a collar 21 having a forked projection 22 thereon with which a projecting pin 23 of a ratchet wheel 24, loosely mounted on said shaft, is adapted to be coupled, so that during 55

rotation of the ratchet wheel motion is transmitted therefrom to the shaft and its selector arm 19 and during axial movement of such shaft its collar 21 remains coupled with the ratchet wheel. 5 This selector-control arm is adapted to selectively register at its outer end with one or another of the push rods 11 through the medium of its collar 17 and when arrested at a given selected position it is adapted to be shifted axially into 10 engagement with such collar to project the selected push rod to a record-selecting position. The ratchet wheel 24 serves to effect the rotation of the selector arm 19 to an operative selective position and to this end a feed pawl 25 is provided 15 which is applied to the lower end of a rock lever 26 pivoted at 27 to the front side of the supporting plate 12 and adapted to be oscillated back and forth in any appropriate remotely-controlled fashion to advance the ratchet wheel 20 in a clockwise direction a predetermined distance to pre-set the selector arm in proper radial registering relation with the push rod companion to a given remotely-selected record. As shown in Figures 1 and 3, the remote control advancement 25 of the ratchet wheel 24 and the selector control arm may be effected by means of a solenoid 28 included in the remote control assembly and circuit hereinafter described and having its plunger 29 connected by a link 30 with the upper end of 30 the rock lever 26. Upon intermittent energization of the solenoid, the rock lever is actuated in a direction to actuate the ratchet wheel a distance of one tooth, and upon the de-energization of the solenoid, a spring 31 returns the solenoid 35 plunger and the rock lever to initial position. A spring 32 connected to the ratchet wheel 24 tends to rotate it in a counter-clockwise direction, and, in the retracted position of the rock lever 26, the feed pawl 25 is held out of engagement with the 40 ratchet wheel 24 by a pin 33 which is adapted to abut against the pawl in the manner shown in Figure 3.

The axial movement of the shaft or plunger 20 to shift the selector-control arm 19 in a forward direction to project a registering push rod 11 to a record-selecting position, is adapted to be actuated in any appropriate remotely controlled fashion, as for example, by a solenoid 34 operatively associated with the shaft or plunger, in 50 the manner shown in Figure 2, such shaft or plunger constituting the actuated element or plunger of the solenoid. Upon energization of this solenoid, the plunger 20 and its selector control arm 19 is shifted forwardly to project a selector rod to a selective position and upon the de-energization of such solenoid a spring 35 applied to the plunger 20 and interposed between the shaft collar 21 and ratchet wheel 24 serves to restore the solenoid plunger and selector control arm to its initial position. During the reciprocating movements of the shaft or plunger 20, its collar 21 remains in rotative coupling engagement with the ratchet wheel 24 through the medium of the connection 22, 23.

65 Also associated with the ratchet wheel 24 is an escapement pawl or dog 36 pivoted at 37 on the supporting plate 12 alongside the ratchet wheel which normally serves to prevent movement of the latter in a counter-clockwise direction under the tension of the spring 32. The pawl is adapted to be released from engagement with the ratchet wheel during restoring movements of the ratchet and associated parts and for this purpose is remotely controlled in any 70 appropriate fashion, as through the medium of

an electromagnet 38, the pawl having an extension 39 thereon which serves as an armature so that when the magnet is energized, the pawl is retracted from engagement with the ratchet wheel. A spring 40 constantly urges the pawl 5 to a normal position in engagement with the ratchet wheel. It is desirable to retain the escapement pawl 36 out of engagement with the ratchet wheel 24 for a longer duration of time than that effected by the magnet 38 and for this 10 purpose I provide a pivoted keeper 41 normally urged to swing downwardly by a spring 42 and having a shoulder 43 at its free end adapted to interlock behind a lateral projection 44 formed on the pawl 36 when the latter has been shifted 15 to a retracted position by the magnet 38. At a predetermined time in the cycle of operations, when the ratchet wheel 24 is urged by its spring 32 in a counter-clockwise direction, a pin 45 projecting from the face of the ratchet wheel is 20 adapted to encounter the pivoted keeper 41 and lift it from interlocking engagement with the pawl 36, thereby permitting that pawl to return to its normal position in engagement with the ratchet wheel. In the normal position of the 25 parts, the push rod control arm 19 will assume a position about half way between the lowest and highest numbered push rods 11, so that if the phonograph is equipped with a coin device and coins are deposited therein, selections of 30 records can be made only with the instrument push buttons.

The remote control unit, which governs the push button control mechanism of the phonograph includes manual selector elements corresponding in number to the push rods 11 and is coin-controlled, and as shown in the drawings, is designed for the deposit of one coin at a time, say, a nickel. Upon the deposit of such a coin, an electric circuit is closed at one point in preparation 35 for automatically closing the circuit at other points including the solenoids 28 and 34 for effecting the automatic selection of a desired record which has been selected from the remote control unit or wall box. This control unit is 40 preferably constructed as follows:

The operative parts of this unit are arranged in a coin-controlled wall box or casing 46 which may be mounted at any desired point remote from the machine or phonograph to be controlled 50 and in the upper front portion of which is arranged a stationary dial plate 47 disposed axially about a shaft 48 journaled in the casing and having an annular row of push buttons or rods 49 corresponding in number to the phonograph 55 selector buttons 11 and projecting through the dial plate in the manner shown in Figure 5 for ready selective manipulation by the patron to initiate the operation of mechanism governed thereby for accomplishing remote selection of a 60 record. The inner or shank portions 50 of the push buttons are guided in a plate 51 arranged within the casing about the shaft 48, and each button is provided intermediate its shank and button-head with a forwardly tapering or frusto 65 conical head 52 and an annular notch or groove 53 formed between such heads. Loosely mounted on the shaft 48 in the operating plane of the frusto-conical heads 52 of the push buttons, is a rotatable button-latching plate 54 having notches 70 55 in its periphery with which the companion conical heads of the push buttons are adapted to register. These notches are preferably shaped in the manner shown in Figures 4 and 6 and the straight edge 56 of each notch engages the pe- 75

periphery of the conical head 52 of the companion push button, so that upon depressing a push button to a selective position the conical head acts as a wedge and turns the plate 54 a fraction of a revolution in a clockwise direction, viewing Figures 4 and 8, with the push button notch 53 registering with the adjoining plate-edge 56 to releasably retain the push button in its fully depressed position. A spring 54* is connected to the latch plate 54 and tends to turn it in a direction to bring the straight edges of the plate-notches in abutting relation to the buttons. Should a second button be depressed, its conical head will engage the edge of the companion 15 registering notch in the plate 54 and similarly advance the plate, and during this advance of the plate the first-depressed button will accordingly be disconnected from interlocking engagement with the plate by reason of the opposing 20 edge of the companion notch receding or being radially displaced from and clear of the notch 53 in such push button. These push buttons serve to close an electric circuit across adjoining contact plates or spiders 57, 58 mounted on the 25 shaft 48 inwardly of the plate 51 and insulated from the shaft and from each other, each plate being notched in the manner shown in Figure 8 to provide contact tongues 59 positioned radially in alignment with the respective push buttons 30 49, there being as many tongues as there are push buttons, so that whenever a push button is depressed at the wall box to remotely select a record at the phonograph, the companion tongues 35 59 of the respective contact plates 57, 58 are brought together to close a circuit for a purpose which will be hereinafter described. The contact plates are more or less yieldable and the outer plate 57, against which the push buttons 49 abut when depressed, is faced with an insulating 40 material and each tongue 59 of such outer plate likewise functions as a spring to restore the depressed push button to a retracted position whenever a subsequent button is depressed to unlatch the first depressed button from the button-lock plate 54. Each push button 49 is also 45 provided with an inwardly-facing radial lug 68 which extends into a companion notch in the lock-plate 54 and bears at its side against the notch-edge 56.

50 Fixed on the inner end of the shaft 48 is a pinion 61 meshing with a gear rack 62 attached to the plunger 63 of a solenoid 64 which is adapted to be energized to rotate the pinion and shaft in a clockwise direction, viewing Figure 4, whenever 55 a selection is made and a coin deposited in the wall box. A spring 65 connected to the solenoid-plunger tends constantly to restore it to its elevated position and to turn the pinion-shaft in a counter-clockwise direction, which movement 60 constitutes the effective operative stroke in remotely selecting a given record at the phonograph. Also fixed on the shaft 48 adjacent its outer end is a drum 66 having a pawl 67 pivoted at one side thereof adjacent its periphery for 65 engagement with a ratchet wheel 68 loosely mounted on the shaft. Associated with this ratchet wheel to move therewith is a gear 69, the latter meshing with a pinion 70 mounted on a counter shaft 71 suitably journaled in the casing 70 46 below and parallel to the shaft 48. The drum 66 is adapted to rotate in spaced relation within the annular row of push buttons 48 and is so positioned that when a button is depressed to a selective position the lug 68 thereof will be in the 75 plane of the drum but clear of its periphery.

Arranged partially within the latter and projecting outwardly through an opening 72 in its periphery is an arcuate spring pawl 73 whose projecting free end is in the path of and adapted to engage the lug 68 of a projected push button, 5 so that during the rotation of the drum in a clockwise direction by the energized solenoid 64, the pawl abuts the lug of the projected button and rocks the same about its axis to turn the notched plate 54 in a like direction to release it 10 from coupling engagement with the button notch 53, whereupon the companion button-engaging tongue 58 of the contact plate 57, which is under tension at this time, will automatically restore the selected button to its retracted position and 15 break the circuit of the solenoid at the contact plates 57, 58. Thereupon, the solenoid-plunger spring 65 will restore the solenoid to its initial position and simultaneously therewith turn the drum 66 in a counter-clockwise direction so that 20 its pawl 67 will likewise turn the ratchet wheel 68 and attached gear 69. Such movement of the parts is arrested at the initial starting position of this cycle of operations by a stop screw 74 disposed in the path of movement of the pawl 67, as 25 shown in Figures 4 and 6, and in a radial plane between the lowest and highest numbered push buttons 48. The number of teeth on the ratchet wheel preferably exceeds the number of push buttons by two, whereby to give the necessary 30 operating clearance between the heel of the pawl 67 and the stop screw 74.

During the effective movement of the ratchet wheel 68 and gear 69 in a counter-clockwise direction, viewing Figure 4, motion is transmitted 35 to the pinion 70, such pinion being revolved one revolution for each tooth-distance of travel of such wheel. Also mounted on the pinion shaft 71 is a crank disk 75 having a connecting link 76 connected at one end thereto and at its other end 40 to a freely oscillating disk 77 on the pinion-shaft or other adjoining part of the casing 46. Projecting from the link 76 is a pin 78 which oscillates back and forth in response to the turning of the crank disk and in the path of which is disposed a normally open switch 79 controlling the circuit of the solenoid 28 which latter in turn governs the ratchet wheel 24 for properly positioning the selector control arm 19 radially in 45 register with the remotely-selected push rod 11. 50 The oscillating disk 77 acts to retard the backward movement of the connecting link so that the pin 78 will close the solenoid-controlling switch 79 with intervals of uniform duration, each closing action of the switch effecting a synchronized movement of the ratchet wheel 24 with that of the ratchet wheel 68, the switch being momentarily opened and closed during each revolution of the pinion 70 or for each tooth-distance of 55 counter-clockwise travel of said ratchet wheel 68. 60

Associated with the remote control unit or wall box is a coin control switch device which is so designed that a coin must be first deposited and then a selection of a desired record made at the wall box to establish a circuit including the switch 18 which controls the solenoid 28 for setting the push button actuating arm 19 in radial alignment with that selector button at the phonograph companion with that selected at the wall box, and further, to establish a circuit which will cause the solenoid 28 to be energized to push the selected button 11 to select position and also start the phonograph in operation, subsequent to which operations the coin-established circuits are again opened and the parts controlled there- 70 75

by restored to their initial positions. This coin control switch mechanism includes a pivoted coin-intercepting paddle 80 disposed in the path of the coin chute (not shown) and whose arm 81 constitutes the movable element of a butterfly switch, the fixed element of such switch being indicated at 82 and connected by a wire 83 to the power line 84, while the companion movable switch element is connected by a wire 85 with the push button solenoid 34 whose coil is connected to the other power line 86. A vertically-swinging lever 87 pivoted intermediate its upper and lower ends at 88 has a lateral extension 89 at its lower end disposed beneath the coin-intercepting paddle, so that when the coin engages the latter it swings it downwardly against the lever-extension 89 and is temporarily arrested with the coin in a trapped position. This movement of the paddle is not sufficient, however, to close the switch 81, 82, but it does act to close a switch for governing the solenoid 28 controlling the phonograph push button control arm ratchet 24 and the solenoid 64 of the wall box, such switch including the elements 90, 91, the fixed element 90 thereof being connected by a wire 92 with one of the terminals of the solenoid 64, the other terminal thereof being connected to the contact plate 58 and the companion contact plate 57 being connected to the power line 84. The movable element 91 of this solenoid-controlling switch is connected to the power line 86 and is operatively associated with the pivoted paddle 80 so that it is tripped to closed position by a coin during the initial swing of the paddle to its arrested position against the extension 89 of the lever 87. The ratcheting solenoid 28 is connected to the power line 86 and to one of the terminals of the switch 79, the other terminal of such switch being connected to the other power line 84, so that when the coin switch 90, 91 is closed and the selector switch 79 intermittently closes the ratchet wheel 24 will be advanced.

A spring 93 serves to normally resist movement of the lever 87 out of the position shown by full lines in Figure 4. At its upper end this lever has a pivoted trip dog 94 disposed in the path of a radial tappet arm 95 fixed on the shaft 48. This tappet arm, as shown by full lines in Figure 4, in the normal non-selective position of the parts, assumes a position to the right of the trip dog 94 and which is a position subsequent to a tripping operation. When a selection is made by depressing one of the wall box selector buttons 49, the tappet arm is moved to the other side of the trip dog simultaneously with the turning of the drum 66 to a position as predetermined by the depressed push button. At the terminal end of the counter-clockwise movement of the drum 66 and associated parts which govern the corresponding movement of the ratchet wheel 24 and selector control arm 19 to a position aligned with the companion phonograph push button, remotely selected by the wall box push button, the tappet arm 95 encounters the trip dog 94 and rocks the lever 87 in a direction to swing its extension 89 from beneath the paddle 80 to thereby release the trapped coin and cause the paddle to be pivoted sufficiently to close the switch 81, 82. This causes the button-press-solenoid 34 to become energized to automatically shift the companion remotely-selected push button of the phonograph to a selected position. Simultaneously with this operation the motor 96 of the phonograph is closed through the medium of a magazine switch 97 connected in series with the solenoid 34 where-

upon the record selected is brought into a playing position and played. When the trapped coin is released and allowed to drop by gravity into the coin box, the lever 87 and tripper paddle 80 return to their initial positions and the circuit is again broken at the switches 81, 82 and 90, 91, causing the button-press-solenoid plunger 20 with its selector control arm 19 to return to its initial position under the tension of the spring 35.

During the restoring movement of the solenoid-plunger 20, means are provided for closing the circuit of the ratchet release magnet 38 to release the pawl 36 from the ratchet wheel 24 and permit the latter and the parts movable therewith to return to initial or selector-starting position under the action of the spring 32. For this purpose, a normally open switch 98 is included in the circuit of the magnet 38 which is connected to the feed wires 84, 86, and applied to the plunger 20 of the solenoid 34 and in the path of this switch is a trip dog 99, which, on the return movement of the plunger to its initial position, encounters and momentarily closes the switch 98 to release the pawl 36 from the ratchet wheel 24. As previously described, the pawl is thereupon held in such released position by the keeper 41.

If desired an indicator including a dial 100 and pointer 101 may be applied to the face of the remote control casing with the dial movable with the shaft 48, so that the patron may observe the selecting movements after a given push button 49 has been depressed and a coin deposited. Should another button be depressed before the first one has been properly registered at the phonograph, it will close the circuit of the solenoid 64 because under such conditions the latter has not had time to return and break the circuit at 90, 91. This will cause ratchet wheel 68 to operate again an unknown number of times and will merely play a wrong selection.

I claim as my invention:

1. Means for remotely controlling a plurality of selector elements, comprising a control member disposed in operative relation to said selector elements for selective movement in registering alignment with one or another of said elements and for an operative movement in a direction to actuate an alining selector element to selecting position, a selector device remote from the selector elements including an arrangement of manually-selective push buttons simulating that of the selector elements and corresponding in number thereto, a selector-registering member movable to a plurality of selective positions relative to said push buttons, means governed by said push buttons for predetermined the selective movement of said member in accordance with a button selected, means operatively connected to said control member and said selector-registering member and governed by the latter for setting the control member in alignment with a selector element companion to the push-button selected, and means for operating said control member in a direction to actuate the alined selector element to selecting position.

2. Means for remotely controlling a plurality of selector elements, comprising a control member disposed in operative relation to said selector elements for selective movement in registering alignment with one or another of said elements and for an operative movement in a direction to actuate an alining selector element to selecting position, a plurality of remotely-disposed, manually-selective push buttons corresponding in number to the selector elements, a selector-registering

mechanism correlated with said push buttons and movable to different selecting positions, electric means operatively connected to said selector-registering mechanism for actuating it, switch means in the circuit of said electric means disposed in companion operative controlling relation with said push buttons for governing the selective movements of said selector registering mechanism, complementary means associated with the latter and said push buttons for predetermining the degree of movement of said registering mechanism and the opening of said switch means in accordance with a given push button selected, means operatively connected to and synchronized with said selector-registering mechanism for moving said control member in registering alignment with the selector element companion to the push button remotely selected, and means for actuating said control member in a direction to move such registered selector element to a selective position.

3. Means for remotely controlling a plurality of selector elements, comprising a control member disposed in operative relation to said selector elements for selective movement in registering alignment with one or another of said elements and for an operative movement in a direction to actuate an alining selector element to selecting position, a plurality of remotely-disposed, manually-selective push buttons corresponding in number to the selector elements, a selector-registering mechanism correlated with said push buttons and movable to different selecting positions, electric means operatively connected to said selector-registering mechanism for actuating it, switch means in the circuit of said electric means disposed in companion operative controlling relation with said push buttons for governing the selective movements of said selector registering mechanism, movable means disposed in operative relation with said push buttons for releasably latching a selected push button in switch-closing position, complementary means associated with the selector registering mechanism and the push buttons for predetermining the degree of movement of said mechanism in accordance with a given push button selected, said complementary means being engageable at a predetermined time with and causing a displacement of said latching means to release the selected push button to switch-opening position, means operatively connected to and synchronized with said selector-registering mechanism for moving said control member in registering alignment with the selector element companion to the push button remotely selected, and means for actuating said control member in a direction to move such registered selector element to a selective position.

4. Means for remotely controlling a plurality of selector elements, comprising a control member in operative relation to said selector elements for selective movement in registering alignment with one or another of said elements and for operative movement in a direction to actuate an alining selector element to a selecting position, a plurality of manually-selective elements corresponding in number to and remote from said first-named selector elements, a selector-registering member movable to a plurality of selective positions relative to said manually-selective elements, means operatively connected to and governed by said manually-selective elements for predetermining the selective movement of said selector-registering member, means operatively connecting said control member and said selector-registering member and governed by the latter for setting the

control member in alignment with a selector element companion to the manual selective element selected, and means for operating said control member in a direction to actuate the aligned selector element to selecting position.

5. Means for remotely controlling a plurality of selector elements, comprising an annular row of push buttons corresponding in number to the selector elements, a ratchet feed mechanism including a ratchet wheel having at least as many teeth thereon as there are push buttons and being movable a predetermined distance of one or more teeth in accordance with the push button selected, means disposed in operative relation with said selector elements for movement into registering engagement with one or another of them and in a direction to actuate such registered elements to selecting positions, a ratchet feed mechanism including a ratchet wheel of like characteristics as the first-named ratchet wheel and operatively connected to said selector-element-actuating means for moving it to selective positions of adjustment, and means for rendering the selector-element-actuating means operative in response to a selection made at the push buttons including an electric circuit, an electrical device in said circuit for actuating the ratchet feed mechanism of the push button assembly a predetermined distance in accordance with a given button selected, switch means in said circuit controlled by and corresponding in number and companion to the push buttons for closing the circuit, means operatively connecting the ratchet feed mechanism of said selector-element-actuating means with the push button ratchet feed mechanism to govern and synchronize the movement of the former with that of the latter to bring said selector-element-actuating means into registering operative engagement with the selector element companion to the push button selected, and means for moving the selector-element-actuating means in a direction to move such registered selector element to a selective position.

6. Means for remotely controlling a plurality of selector elements, comprising an annular row of push buttons corresponding in number to the selector elements, a ratchet feed mechanism including a ratchet wheel having at least as many teeth thereon as there are push buttons and being movable a predetermined distance of one or more teeth in accordance with the push button selected, means disposed in operative relation with said selector elements for movement into registering engagement with one or another of them, and in a direction to actuate such registered elements to selecting positions, a ratchet feed mechanism including a ratchet wheel of like characteristics as the first-named ratchet wheel and operatively connected to said selector-element-actuating means for moving it to selective positions of adjustment, means for moving the selector-element-actuating means in a direction to move a registered selector element to a selective position, means for rendering the selector-element-actuating means operative in response to a selection made at the push buttons.

7. Means for remotely controlling a plurality of selector elements, comprising an annular row of push buttons corresponding in number to the selector elements, a ratchet feed mechanism including a ratchet wheel having at least as many teeth thereon as there are push buttons and being movable a predetermined distance of one or more teeth in accordance with the push button selected, means disposed in operative relation

with said selector elements for movement into registering engagement with one or another of them and in a direction to actuate such registered elements to selecting positions, a ratchet feed mechanism including a ratchet wheel of like characteristics as the first-named ratchet wheel and operatively connected to said selector-element-actuating means for moving it to selective positions of adjustment, means for moving the selector-element-actuating means in a direction to move a

registered selector element to a selective position, and means operatively connecting the ratchet feed mechanism of said selector-element-actuating means with the push button ratchet feed mechanism to govern and synchronize the movement of the former with that of the latter to bring said selector-element-actuating means into registering operative engagement with the selector element companion to the push button selected. 5

RUSSELL I. WILCOX. 10
